UNITED STATES PATENT OFFICE.

THOMAS HALL, OF LAWRENCE, MASSACHUSETTS.

SPINDLE FOR SPINNING AND TWISTING MACHINES.

SPECIFICATION forming part of Letters Patent No. 245,487, dated August 9, 1881.

Application filed January 31, 1881. (No model.)

To all whom it may concern:

Be it known that I, THOMAS HALL, a citizen of the United States, residing at Lawrence, in the county of Essex and State of Massachusetts, have invented certain new and useful Improvements in Spindles for Spinning and Twisting Machines; and I do hereby declare the following to be a full, clear, and exact description of the invention, such as will enable others skilled in the art to which it appertains to make and use the same, reference being had to the accompanying drawings, and to the letters or figures of reference marked thereon, which form a part of this specification.

This invention relates to spindles employed in spinning and twisting machinery; and the novelty consists in the construction and arrangement of parts, as will be more fully hereinafter set forth, and specially pointed out in the claims.

Heretofore spindles of the class to which my invention pertains have been cast or forged of one piece of metal, having a boss and spindle arm or blade, leaving an abrupt shoulder at the junction of the two, making the spindle weak and liable to break at this point.

The object of my invention is to overcome this objection, and to furnish a spindle which shall be alike cheap to manufacture and effective in operation.

In the drawings which form a part of this specification, Figure 1 is a longitudinal elevation of the spindle, showing the whirl and tube in section on the same; Fig. 2, a sectional detail view of the same; Fig. 3, a side elevation, showing the spindle in position, with the cap, whirl, and tube to carry the bobbin.

The spindle proper is of steel, and has cast thereon a spirally-grooved boss, having a wrench-head formed upon the lower end of the same, by means of which the position of the spindle may be changed.

A represents or designates the spindle-arm; B, the boss cast thereon; C, the spiral groove upon said boss, in which the set-screw operates to hold it in position; D, the wrench-head; F, the whirl, and G the tube.

Fig. 3, Sheet 2, of the drawings, shows the spindle in working position, with the cap H, whirl F, and tube G.

In operation the spindle passes through the spindle-rail E and the lifter-rail I. The lower or boss end of the spindle is secured to the spindle-rail and firmly held in position by the set-screw a passing through the rail E. When the set-screw is loosened the spindle may be raised or lowered by means of the wrench-head D, and again secured and held by the set-screw a, and the whirl F being mounted upon the tube G, which fits loosely over and upon the spindle-arm A, it revolves freely upon said spindle, and is raised and lowered by the lifter-rail I.

What I claim, and desire to secure by Letters Patent, is—

1. The steel spindle or twisting-spindle A, having the spirally-grooved boss B cast thereon, and having formed on its lower end the wrench-head D, substantially as shown and set forth.

2. The rail E of a spinning or twisting machine, the spindle A, with the boss B, having the spiral groove C cast thereon and formed with the wrench-head D, and the set-screw a, all constructed and combined as shown, and for the purpose set forth.

In testimony whereof I affix my signature in presence of two witnesses.

THOMAS HALL.

Witnesses:

JAMES NEWTON,
FRANCIS A. HALL.
